UNITED STATES PATENT OFFICE.

CHARLES A. MUNSON, OF NEW BRITAIN, CONNECTICUT.

METHOD OF FORMING HINGES.

Application filed April 16, 1926. Serial No. 102,530.

This invention relates to hinges, and has particular reference to hinges for use in connection with automobile doors and the like.

- 5 The object of the present invention is to provide a hinge of this sort which may be economically manufactured, which has great strength and durability, and which has a neat, pleasing and thin appearance.
- 10 A further object of the invention is to provide an improved method by means of which the hinge leaf may be economically manufactured.

More specifically, the aim of the present invention is to provide an improved hinge from sheet metal and which hinge fully meets all requirements. The body portion of the leaf is preferably made of wrought sheet metal of relatively thick gauge so that 15 it will have great rigidity, strength and durability, thus insuring it against twisting, warping or breaking under the weight of the hinged member, such as an automobile door, to which is frequently added a downward 20 pressure by a person entering or leaving the automobile. The knuckle, or knuckles, of the leaf is formed by rolling one end of the blank back upon itself, the knuckle being of reduced thickness so that the hinge, in 25 which the leaf is incorporated, is given a relatively thin and neat appearance. In constructing the hinge leaf, the portion of the blank which is to constitute the knuckle is so shaped and operated upon that there 30 are no observable cracks or crevices in the walls of the knuckle, and the pintle receiving opening of the knuckle is true in its roundness and continuity. By making the knuckle of reduced thickness, the pintle receiving opening of the knuckle may be relatively 35 large as compared to the thickness of the wall of the knuckle in order to prevent strain and possible fracture of the metal constituting the knuckle which might occur 40 were the metal bent about a small radius, while at the same time, the external diameter of the knuckle is maintained within 45 limits which give a thin appearance. Also, a substantial bearing surface between the 50 pintle and the knuckle is obtained.

Other objects will be in part obvious and

in part pointed out more in detail herein-after.

The invention accordingly consists in the features of construction, combination of 55 elements and arrangement of parts which will be exemplified in the construction hereinafter set forth, and the scope of the application of which will be indicated in the appended claims.

In the accompanying drawings, wherein I have shown, for illustrative purposes, one embodiment which the present invention may take;

Fig. 1 is a perspective view of a blank 65 from which my improved hinge leaf may be formed;

Fig. 2 is a plan view of the blank after the end thereof, which is to constitute the knuckle, has been reduced in thickness; 70

Fig. 3 is an edge view of the blank shown in Fig. 2;

Fig. 4 is a view similar to Fig. 2, but showing the side edges of the reduced portion of the blank trimmed; 75

Fig. 5 is an edge view of the blank shown in Fig. 4;

Fig. 6 is a plan view showing the reduced portion of the blank rolled back upon itself to form a knuckle; 80

Fig. 7 is an edge view of what is shown in Fig. 6;

Fig. 8 is a view similar to Fig. 6, but showing the ends of the knuckle portion trimmed; 85

Fig. 9 is an edge view of what is shown in Fig. 8;

Fig. 10 is an edge view of the completed leaf, the opening through the knuckle having been reamed to make the same true 90 and round; and

Fig. 11 is a view showing one form of hinge in which is incorporated my improved leaf.

In carrying out the method of the present invention, a blank, such as shown in Fig. 1, is cut or stamped from a sheet of wrought metal of relatively thick gauge. In the present illustrative disclosure, the blank is shown as having a body or attaching portion 10 and a knuckle forming portion or tab 11 at one end of the body por-

tion, but it is to be understood that this disclosure is by way of illustration only and, obviously, the configuration of the leaf blank will depend upon the type of hinge 5 in which the completed leaf is to be employed. The knuckle forming portion or tab 11 is reduced in thickness, as at 12, for a substantial portion of its length, preferably by swedging or forging this portion of 10 the blank in a cold condition. As will be seen most clearly from Figs. 2 to 5, the depression, formed in the upper face of the tab by the operation of reducing the thickness of the tab, terminates short of the outer 15 end thereof, leaving a portion 13 of substantially the same thickness as that of the body portion 10. The blank, at the juncture of the attaching portion and knuckle forming portion, gradually tapers down in 20 thickness, as at 14, there being an inclined surface 15 between the bottom surface of the depression and the upper surface of the body portion. The swedging or forging operation causes the metal to flow or spread. 25 and thus forms a flash or bulge 18 at each side edge of the tab, and these bulges are trimmed away along the dotted lines of Fig. 2 so as to give the tab the shape shown in Fig. 4. During the swedging or forging 30 operation, or subsequent thereto, as desired, the outer end of the tab may be slightly turned up as indicated in Figs. 3 and 5.

The tab is now rolled back upon itself into generally circular form and, preferably, in 35 this operation, the outer end edge 19 of the tab is engaged with the inclined or tapered surface 15, as shown most clearly in Figs. 7, 9 and 10. During the operation of rolling the knuckle, or subsequently thereto, the 40 blank may be bent or upset, as at 20, to bring the knuckle into the plane of the body portion. The next operation may consist in trimming or milling the ends of the knuckle so as to bring the same from the 45 rough and uneven condition shown in Figs. 6 and 7 to a flat and smooth condition as shown in Figs. 8 and 9. The opening within the knuckle is now made round and true in all respects by a suitable operation as, 50 for example, by means of reaming. The countersunk apertures 21 in the body portion may be made at any desired time during the process.

55 It is of distinct advantage, in carrying out my process, to provide, at the outer end of the tab 11, a portion or rib 13 of greater thickness than the reduced portion 12 of the tab for the reason that, when the tab is rolled upon itself into knuckle form, the metal of the rib will fill in the angle or notch which would otherwise be present within the hole adjacent the seam or joint in the knuckle; and upon reaming out the 60 hole its internal periphery will be continuous and devoid of all perceptible cracks.

or angles, and thus there will be had a very finished joint which in no way mars the appearance of the knuckle. It will be seen from Figs. 9 and 10 that the end edge 19 engages snugly against the inclined surface 15 and that the portion of the blank of normal thickness gradually merges or tapers down, as at 14^a, into the reduced wall of the knuckle. 70

It will be seen that, by proceeding in accordance with the present invention, my improved hinge leaves may be economically formed from sheet metal, each of the steps of the process being relatively simple. Since the leaf is made of wrought sheet metal, and the body portion of the leaf is of relatively thick gauge, a hinge in which my leaf is incorporated will be extremely sturdy and durable. The knuckle portion, while having a wall of lesser thickness than the body portion, is nevertheless relatively strong and particularly so as the operation of cold swedging the knuckle forming portion gives exceptionally high physical qualities thereto. 80 85

In Fig. 11 is shown, for illustrative purposes, a complete hinge, one of the leaves of which is constructed in accordance with the present invention; the other leaf, designated generally by the letter *a*, has at one end an upturned wall or flange 25 which forms a 90 socket for the knuckle 11. The ends of this socket are closed by webs or projections 26 constituting knuckles for the pintle *c*. 95

I claim as my invention:

1. The herein described method of forming hinge leaves which consists in stamping 100 a blank from sheet metal, reducing in thickness a portion of said blank adjacent to, but spaced slightly from, one end thereof, thus providing a narrow portion of normal thickness at the end of said blank, rolling said reduced portion back upon itself, trimming the ends of said knuckle, and reaming the hole of said knuckle. 105

2. The herein described method of forming hinge leaves which consists in stamping out a blank from wrought sheet metal, reducing in thickness a portion of the blank adjacent to, but spaced slightly from, one end thereof by swedging said portion in cold 110 condition, trimming the side edges of said reduced portion, rolling the reduced portion back upon itself into cylindrical form to constitute a knuckle, and then making the hole in said knuckle true and round. 115

3. The herein described method of forming hinge leaves which consists in stamping a blank from sheet metal, reducing in thickness a portion of the blank adjacent to, but spaced slightly from, one end thereof, and thus forming in one face of the blank a depression having at one end an inclined surface merging into the body portion of the blank and at the other end a narrow portion of normal thickness, rolling the portion 120 125 130

of reduced thickness back upon itself into cylindrical form and abutting the end edge of the blank against said inclined surface, trimming the ends of the knuckle and making the hole in the knuckle round and true.

4. The herein described method of forming hinge leaves which consists in stamping a blank from sheet metal, forming a depression in one face of the blank adjacent to,

but spaced slightly from, the outer end thereof, slightly bending up the outer end of said blank which is of normal thickness, rolling the portion of reduced thickness back upon itself into the form of a cylindrical knuckle, and then reaming the hole in the 15 knuckle.

CHARLES A. MUNSON.
